UNITED STATES PATENT OFFICE.

WILLIAM C. BAXTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR USE IN THE MANUFACTURE OF SHOES.

Application filed March 30, 1925, Serial No. 19,347, and in Great Britain May 19, 1924.

This invention relates to machines for use in the manufacture of boots and shoes, and more particularly to machines for use in shaping shoe uppers, in assembling uppers and insoles, or in performing both these operations.

The invention is herein illustrated as embodied in a machine of the type shown and described in Letters Patent No. 1,700,970, granted on my application on February 5, 1929. Machines of this type are especially designed for shaping or molding the heel end portion of the upper off the last over a heel end form and also over an insole to which the molded heel end of the upper is fastened while on the form. It is to be understood, however, that the invention is not limited in its application to machines of this particular type, nor to machines for shaping an upper over a form of the character illustrated as distinguished, for example, from a last.

One important object of the invention is to provide conveniently operable and effective means adapted for use in machines of the above-mentioned type for tensioning an upper about a form. In one aspect, the invention thus has in view the holding of the upper against accidental displacement while the operator has his hands free to adjust the upper materials relatively to the form in such manner as may be necessary to bring them into a proper predetermined position before they are operated upon; and in another aspect the purpose is to assist in the shaping of the upper by drawing it tightly about the form before the shaping or molding pressure is applied. For the accomplishment of these different ends the construction shown comprises spring-operated means for tensioning the upper first lightly about the form while permitting it to be readily adjusted, and additional means operable thereafter to subject the upper to increased forward or lengthwise tension. For certain purposes it is contemplated that prior to the shaping of the heel end of the upper, or the assembling of the upper and the insole, the toe end of the upper will have been previously molded substantially to the shape desired for the finished shoe, and for this class of work the invention further provides upper-tensioning means constructed to take its tensioning purchase on the fore-

part of the upper without impairing the molding of the toe, the construction shown comprising a member shaped to hook under a molded inturned flange at the toe end of the upper and to abut against the inner face of the end of the molded toe, this member being shaped to conform substantially to the contour of that portion of the upper which it engages. An additional useful characteristic of this construction, which facilitates the proper positioning of the work and contributes to uniformity in the shaping of different uppers, is that the upper-pulling member, by engagement with the inturned flange of the molded toe serves to support the forepart of the upper at a predetermined height relatively to the form which is inviolable for all shoes of the same size and style.

Machines of the type illustrated in the above-mentioned Letters Patent comprise in their organization means for applying clamping pressure over the heel end of an insole on the form, for supporting the rear end portions of a welt shoe insole lip against the molding pressure on the upper, and for engaging the upper in jig holes formed therein to position it in predetermined relation to the form. In certain further aspects the present invention aims to provide improved means for engaging the heel end portion of the work to position the latter in predetermined relation to the form, which will be applicable to an organization having one or more of the above-mentioned characteristics. In one important aspect, the invention provides an insole-positioning device, adapted in the construction shown both to clamp the insole on the form and to support the rear end portions of the lip against the molding pressure, which device is movable with the form from an upper-receiving position into position to present the work to the upper-shaping or molding means and remains in operative position during a portion at least of the operation of laying the margin of the upper inwardly over the insole. In another aspect, the invention provides separate work-positioning devices or members arranged to be positioned over the bottom of the insole, one at a distance from the edge of the insole and the other over the margin of the insole, the latter member in the construction shown

being adapted to engage the inturned flange of a molded counter to position the counter in proper relation to the form while clamping the counter flange and the margin of the insole upon the bottom of the form and being movable out of operative position relatively to the other positioning member which, in the construction shown, is adapted to serve both as an insole-clamping member 5 engaging the insole at a distance from its edge and as a lip support, as above described. Such movement of the counter-positioning and clamping means out of operative position makes way for the laying of the margin 10 of the upper inwardly over the insole while the means which clamps the insole at a distance from its edge and supports the lip remains in operative position. In a further aspect, the invention provides a novel organization of work-positioning devices including upper-positioning means movable into and out of operative position, the construction shown comprising upper-engaging jig pins which are mounted for movement away 15 from the form with the device provided for applying clamping pressure over the margin of the insole.

In still another aspect, the invention provides a novel organization of work-positioning means and mechanism for supporting or controlling said work-positioning means. In the construction shown the devices above described for engaging and positioning the work at the heel end are mounted to swing 20 with the form from a work-receiving position into position to present the work to the upper-shaping means, and there is provided means also movable with the form for moving said devices upwardly away from the form to withdraw them from operative position. For returning said work-positioning devices to starting position to make way for further operations on the work, the machine 25 herein shown is provided with a supporting arm which, in addition to upward movement for withdrawing said devices from the work, is mounted also to swing laterally of the form and forwardly about the same axis as the form while the form remains in its work-presenting position.

The above and other features of the invention, including a novel construction and arrangement of upper-jigging means and various novel details of construction and combinations of parts, will now be more particularly described by reference to the accompanying drawings and thereafter pointed out in the claims.

In the drawings, 60 Fig. 1 is a view partly in right hand side elevation and partly in section of as much of the machine as it is necessary to show for an understanding of the invention;

Fig. 2 is a view in side elevation of a 65 portion of the structure shown in Fig. 1,

illustrating how the upper is tensioned forwardly about the heel end form and how the work is positioned at the heel end;

Fig. 3 is a plan view of the form and of portions of the upper tensioning device, with 70 the position of an insole indicated by dotted lines;

Fig. 4 is a section on the line 4—4 of Fig. 2 on an enlarged scale;

Fig. 5 is a front elevation, on an enlarged 75 scale, of the structure shown in Fig. 1, with the parts in the positions that they assume when the upper is mounted on the jig pins and tensioned about the form;

Fig. 6 is a view in front elevation, on a 80 larger scale than Fig. 5, of the work-positioning devices in operative relation to the form;

Fig. 7 shows substantially the same parts 85 as Fig. 6, together with the heel band and wipers, at a later stage in the operation of the machine;

Fig. 8 is a vertical central section longitudinally of the work-positioning devices shown in Figs. 6 and 7, and 90

Fig. 9 is a view in left hand side elevation of a portion of the structure shown in Figs 1 and 5.

The machine shown in the above-mentioned Letters Patent is a twin machine comprising two sets of operating instrumentalities for operating respectively upon right and left shoes, but only one of these sets of instrumentalities need be and is herein shown for the purpose of an explanation of the present invention. For shaping or molding the heel end portion of the upper materials there is provided an inner heel end form 2 which is supported on a rod 4 mounted for lengthwise upward and downward movements in a form carrier 6, the latter being mounted for swinging movements on a pivot shaft 8 at the base of the machine. The form 2 is provided with pins 10 which are fixed thereon and are arranged to project through jig holes formed in the heel end portion of an insole to position the insole in exact predetermined relation to the form. Co-operating with the form 2 is upper-shaping means comprising 95 a heel band 12 within which the form is carried by movement of its carrier 6 about the shaft 8, this movement being effected by a cam (not shown) which is mounted on a cam shaft 14 and operates a lever 16 connected by means of a lengthwise extensible link 18 to the carrier 6. It will be understood that after the insole and the upper materials have been mounted on the form 2 and 100

have been positioned in the manner more particularly hereinafter described, the machine is started, and the form 2 with the shoe materials thereon is carried rearwardly into the band 12 and the latter is closed 120 to shape and clamp the upper about the 125 130

form, the carrier 6 being locked in its rearward position by members 20 which engage lugs 22 thereon. Thereafter wipers 24 are operated to wipe the upper materials inwardly over the insole and tacks are driven by means not herein shown to secure the materials to the insole. The wipers are then retracted, the heel band is opened and the form carrier 6 is returned to its initial position to permit the work to be removed from the form 2. These various parts and their operations are more fully shown and described in the Letters Patent mentioned.

For purposes of the present invention there is provided a novel construction and arrangement of work-positioning means cooperating with the form 2 comprising, as herein shown, means for jiggling the upper relatively to the form, for clamping the heel 20 end of a welt shoe insole on the form and supporting the rear end portions of the insole lip against the inward pressure of the wipers, and for positioning a flanged counter relatively to the form. Upon the upper 25 end of an arm 26, hereinafter more particularly described, there is pivotally mounted at 28 (Figs. 1 and 8) a supporting block 30 which carries an insole-clamping and lip-supporting member or plate 32 formed to 30 engage the insole at a distance from its edge sufficient to permit the overwiping operation of the wipers and provided with a cylindrical shank portion 34 which is mounted for sliding movement in a recess formed in 35 the block 30. The member 32 is normally depressed by a spring 36 which is mounted within the shank portion 34 and bears at its upper end upon the arm 26. To limit downward movement of the member 32 and to 40 prevent it from turning, there is provided a pin 38 which is fast on a spring plate 40 secured to the block 30 and projects into a slot 42 formed in the shank 34. The pin 38 has a knob 39 thereon by which the pin 45 may be withdrawn from the slot 42 against the resistance of the spring plate 40 to permit differently shaped clamp members 32 to be utilized for different sizes of shoes, this being desirable in order that the member 32 may lie close to the insole lip *a* at the 50 opposite sides of the insole to support the lip against the pressure of the wipers as they wipe the upper materials inwardly and shape them against the ends of the lip in front of the heel seat, as described in the Letters Patent mentioned. It will be evident that the spring 36 tends to tip the block 30 about its pivot 28, such tipping movement being limited by engagement of the block 55 with the arm 26, and this arrangement affords provision for yield to permit the clamp member 32 to seat itself evenly upon the insole. It will be understood that, to apply the member 32 to the insole, the block 60 65 30 is carried downwardly by bodily move-

ment of the arm 26, as more particularly hereinafter described, the spring 36 yielding to permit the block 30 to continue its movement after the member 32 has engaged the insole. The member 32 is provided with openings 44 and 46 to receive the ends of the jig pins 10.

Slidably mounted also for vertical movements on the block or support 30 is an additional clamp member 48 which serves as 75 a jig pin carrier and has mounted thereon a plurality of jig pins 50 for engaging the marginal portion of the upper in pig holes previously formed therein to position the upper. These jig pins may be four in number, as in the machine of the earlier Letters Patent, two being positioned for engagement with the upper at its rear end at opposite sides of the back seam, and two others for engaging it farther forwardly at the sides of 80 its heel end portion, although the invention is not limited to this particular number of pins. In the present construction the jig pins 50 are pivotally mounted on the member 48 and are curved about the axes of their 85 swinging movements, so that when they are in position for engagement with the upper they serve as hooks upon which the upper may be suspended with ample security 90 against its displacement. Connected to each 95 of the pivotally mounted jig pins 50 is a gear sector 52 in engagement with rack teeth 54 formed on the block 30. Springs 56 are mounted in the block 30 and bear at their lower ends against the member 48 to hold 100 this member normally in a position determined by its engagement with a ledge 58 on the block 30. When the parts are in this relation the jig pins 50 are held in refracted 105 positions, as illustrated in Figs. 7 and 8.

The member 48 is shaped, as illustrated in Figs. 1 and 8, so as partially to embrace the clamp member 32 at the rear of the insole lip, and it is thus adapted to press the lining and the inturned flange of the molded 110 counter, where such a counter is utilized, down upon the margin of the insole and thereby to position the counter in proper relation to the form and the other shoe parts while also clamping the margin of the insole 115 down upon the form. It will be understood that when the arm 26 is operated to move the block 30 downwardly toward the form 2, the member 32 first engages the insole, and thereafter the member 48 comes into engagement 120 with the materials that lie over the margin of the insole. By continued downward movement of the block 30 after the member 48 has arrived in clamping position, the jig pins 50 are swung outwardly into position 125 for the upper to be mounted thereon.

The arm 26, which carries the block 30 and the parts supported thereby, is mounted to swing laterally of the form 2 about a pivot shaft 62 which is mounted in a bracket 64 130

projecting from a sleeve member 66 which serves as a support for the arm. The sleeve member 66 is mounted to slide upwardly and downwardly upon a guide rod 68 which is fast at its lower end in a bracket 70 mounted to swing forwardly and rearwardly about the same shaft 8 which serves as a pivotal support for the form carrier 6. It will thus be seen that the work-positioning and clamping means above described is mounted independently of the form 2 to swing with or relatively to the form about the same axis and also to swing laterally of the form into or out of position over the bottom of the form. At its upper end the rod 68 is provided with a head 72 which embraces a stationary guide member 74 to guide the rod in its movements about the shaft 8, and forward swinging movement of the rod is adjustably limited by means of a stop screw 76 which is mounted in a downwardly projecting end of the guide member 74 and is arranged to engage the head 72 on the rod. By this means the position of the arm 26 relatively to the form carrier 6 may be so determined that when the arm is swung about its pivot 62 to carry the work-positioning devices over the form 2, the clamping members 32 and 48 will be properly positioned lengthwise of the form and the insole. The arm 26 is swung to its idle position about its pivot 62 by means of a spring plunger 78 which engages a part of the bracket 64, and movement of the arm 26 in this direction is limited by means of a slotted link 80 (Fig. 9) one end of which is pivoted on the sleeve member 66. To assist the operator in swinging the arm 26 toward the form a handle 82 is provided on the upper end of the arm. The arm is further guided and steadied in its swinging movements about the pivot 62 by means of a sliding connection between the arm and the sleeve member 66 comprising a plate 84 on the sleeve member and a co-operating plate 85 on the arm, the plate 85 having a projection 87 which engages the plate 84 to limit swinging movement of the arm. After the arm 26 has been swung to carry the block 30 and the parts supported thereby into position over the form, and as the supporting sleeve 66 is then moved downwardly in the manner hereinafter described, the arm 26 is locked to the form carrier 6, both to assist in accurately alining the work-positioning means with the form and to cause this means to be swung rearwardly with the form carrier 6 as the work is carried into the heel band 12. For this purpose the arm 26 is provided with a lug 86 having a hole formed therein to receive a pin 88 which is fast on the form carrier 6.

The supporting sleeve member 66 is normally upheld by means of a spring 90 which bears at its lower end upon a collar 92 ad-

justably secured to the rod 68. For moving the sleeve member downwardly along the rod 68 to carry the work-positioning means on the arm 26 toward the insole-engaging bottom face of the form 2, the bracket 64 is connected by means of a link 94 to a treadle 96. For holding the member 66 and the parts supported thereby against return upward movement, there is provided a clutch or retaining device comprising a friction clutch member 98 pivoted at 100 on the member 66 and arranged to engage a wear plate 102 fast on the rod 68. The clutch member 98 is secured adjustably to an arm 104 which is also pivoted at 100 on the member 66, this arm extending rearwardly and being engaged at its rear end by a spring plunger 106 mounted in a recess in the member 66 to hold the clutch member 98 in operative position. The member 98 thus permits the sleeve member 66 to be moved downwardly by the treadle 96, but locks it against return upward movement. In order to unlock the member 66 and permit it to move upwardly, it is necessary to swing the arm 104 about its pivot against the resistance of the spring plunger 106, and for this purpose the arm extends forwardly into position to be engaged by the foot of the operator in case it is desired to release the shoe materials and to rearrange them after the members 32 and 48 have been moved to clamping position. The machine is also provided, as more fully hereinafter explained, with automatic means for unlocking the sleeve member 66 in time relation to other operations, comprising a cam-controlled lever 108 which is pivotally mounted at 110 (Fig. 1) and extends into position under the rear end of the arm 104 (Fig. 9).

At that time in the cycle of the machine when the sleeve member 66 and the parts supported thereby are returned to their uppermost positions and the arm 26 is released by the pin 88 to permit it to swing about its pivot 62, the sleeve member 66 and the rod 68 are swung forwardly about the shaft 8 by power-operated means comprising a bell-crank lever 112 (Fig. 1) provided with a roll 114 which engages a wear plate 116 (Fig. 9) on the member 66, the bell-crank being operated by a cam (not shown) on the cam shaft 14.

The machine herein shown is further provided, for purposes of the present invention, with means for engaging the upper and pulling or tensioning it forwardly about the form 2, both to assist the operator in positioning and arranging the upper materials and to draw them tightly over the form before they are engaged by the heel band. As herein illustrated the machine is designed for use on uppers that come to the machine each with its toe end portion already molded substantially to the shape desired for the

finished shoe and having a flange *b* formed to lie over the margin of the insole, the flange herein shown comprising inturned and upturned portions for welt shoe work, and the upper pulling means is constructed to engage the molded toe end of the upper without impairing the molding of the toe. The construction shown comprises an upper-engaging member 118 of spring steel which 10 is curved to extend upwardly and rearwardly and then downwardly and forwardly under the molded flange *b* at the end of the toe and has its end face rounded to conform substantially to the curvature of the end face 15 of the toe, as illustrated by dotted lines at 119 in Fig. 3. By reason of the shape of the member 118, only its extreme end portion, curved as illustrated, has tensioning purchase on the upper, and since the member thus 20 conforms substantially to the shape of that portion of the toe which it engages, and since it pulls substantially along the median line of the upper, there is no danger of 25 distorting the shape of the toe by the force of the pull.

The member 118 is mounted on a bracket 120 which is supported on a rod 122 formed on the upper end of a lever 124. This lever carries a pin 126 which is slidably mounted 30 in a slot 128 formed in a bracket or abutment 130 fast on the form carrier 6. A spring 132 connected to the lower end of the lever 124 tends to swing the upper end of the lever forwardly about the fulcrum provided 35 by the pin 126 and the bracket 130, the lever being further controlled by means of a hand lever 134, as more fully hereinafter described. The member 118 is adjustable in a 40 guideway provided in the bracket 120 for different lengths of uppers, and is held in adjusted position by means of a spring-controlled pin 136 which is arranged to enter any one of a number of recesses 138 formed in the member 118. Provision is afforded 45 for limited turning movement of the bracket 120 about the rod 122, the bracket having thereon a pin 140 projecting downwardly within a recess between two opposite stop screws 142 that are adjustably mounted in 50 a collar 144 adjustably secured on the rod 122. By reason of such turning movement of the bracket 120 the member 118 is permitted to accommodate itself to differences of "swing" of different uppers.

55 The hand lever 134 is pivotally mounted upon the form carrier 6 and is shaped to embrace the lever 124. It has adjustably mounted thereon a pin 146 which is arranged to engage either one of two opposite cam faces 148 and 150 on the lever 124, the cam face 150 being formed on a downwardly projecting hook portion 152 of the lever. When the parts are in idle position the pin 146 may lie in a recess 154 in the lever 124, 60 being at this time below the projection 152,

so that by pushing on the member 118 the operator is enabled readily to swing the lever 124 rearwardly against the comparatively light resistance of the spring 132 far enough to permit the end of the member 118 to be readily hooked under the flange *b* of the molded toe of an upper. The spring 132 will then act on the lever 124 to pull the upper materials forwardly about the form 2 under light tension sufficient to hold 75 them from slipping downwardly over the form, while at the same time the member 118 by engagement with the inturned flange of the molded toe supports the forepart of the upper at a predetermined height relatively 80 to the form, thus leaving the operator free to position an insole on the form and to adjust the upper materials, including the counter and the lining, about the form and over the margin of the insole. After the upper 85 materials have thus been arranged, and after the upper-jigging and work-clamping means have been brought into operative position and the upper has been hung upon the jig pins 50, the lever 134 is moved upwardly by 90 the operator and by engagement of the pin 146 with the cam face 150 the upper end of the lever 124 is swung forwardly to apply increased tension to the upper materials and thus to pull them tightly about the form before they are carried rearwardly into the heel band. At the end of the upward movement of the lever 134 the pin 146 seats with 95 in a recess 156 above the cam face 150, so that the lever is held against downward movement when it is released by the operator. As the increased tension is thus applied to the upper by upward movement of the lever 134, the lever 124 is forced bodily 100 forward and may be swung to some extent about the point of engagement of the member 118 with the upper and the pin 126 is carried away from the rear end of the slot 128, as illustrated in Fig. 2, so that the lever 124 then fulcrums on the pin 146 instead of 105 on the pin 126, and the effectiveness of the spring 132 in its pull on the upper is increased by reason of the increased leverage 110 due to the shifting of the fulcrum point of the lever 124 nearer to the upper-engaging 115 member 118.

In the operation of the machine, briefly summarized, the operator places the heel end of the upper materials about the form 2 and engages the molded toe with the upper-pulling member 118 under light spring tension, as above described. He then places an insole *c* upon the form over the pins 10 with its toe end resting upon the member 118, and positions and adjusts the counter *d* and the lining *e* about the form and over the margin of the insole. As herein illustrated the counter is molded with an inturned flange adapted to lie over the margin of the insole, this flange having its end portions up- 120 125 130 135

turned to lie close to the rear end portions of the insole lip, as shown in Figs. 6 and 7 and more in detail in the earlier Letters Patent. Thereafter the operator swings the 5 arm 26 to carry the upper-jigging and work-clamping means over the form 2, and by depression of the treadle 96 forces the insole-clamping and lip-supporting member 32 into engagement with the insole and the member 48 into positioning and clamping engagement with the inturned flange of the counter over the margin of the heel end of the insole at the rear of the insole lip. By 10 continued downward movement of the support 30 the jig pins 50 are swung outwardly into operative position. If it should be observed at any time in these operations that the work is not clamped in proper position, the operator may depress the clutch controlling arm 104 by his foot and thus unlock the 15 sleeve 66 and permit the upper-jigging and work-clamping means to be retracted more or less from the form 2. When the materials have been properly clamped, the operator 20 hangs the upper upon the jig pins 50 which enter the jig holes previously formed in the margin of the upper, as illustrated in Fig. 6, and then slips the heel end of the upper downwardly about the form 2 enough to 25 straighten it. The operator then raises the lever 134 to apply increased forward tension to the upper materials and tighten them 30 over the form.

The shoe materials having been positioned 35 relatively to the form 2 and the upper tensioned about the form in the manner above described, the operator starts the machine, whereupon the form carrier 6, the upper-tensioning means, and the upper-jigging and work-clamping means are swung rearwardly 40 as a unit to carry the form 2 and the shoe materials into the heel band 12, and the heel band is closed about the form 2 to shape and clamp the upper materials against the 45 end and side faces of the form. The cam-controlled lever 108 is then moved upwardly to unlock the sleeve member 66 from the rod 68 and thus cause the arm 26 and the supporting member 30 to rise far enough to 50 withdraw the jig pins 50 from the upper and to remove the clamp member 48 from engagement with the shoe materials clear of the path of the wipers, as illustrated in Fig. 7. The movement of the lever 108, however, 55 is stopped at such a point as to cause the insole-clamping and lip-supporting member 32 to remain in engagement with the insole to serve as a support for the insole lip against the pressure of the wipers, it being understood 60 that the clutch member 98 immediately locks the sleeve 66 again as soon as it is released from the pressure of the lever 108. The wipers 24 are now operated to wipe the upper inwardly over the insole, as more 65 fully described in the earlier Letters Patent.

After the wipers have completed their over-wiping operation, a further movement of the lever 108 finally releases the sleeve 66 and causes the arm 26 to be moved by the spring 90 to its uppermost position, withdrawing 70 the clamp member 32 from the insole, whereupon the arm is swung laterally away from the form by the action of the spring plunger 78. At this time also the lever 112 is operated to impart forward swinging movement about the shaft 8 to the sleeve member 66 and the rod 68, thus making way for the tacking mechanism which is moved to operative position over the form and is operated to drive the upper fastening tacks, 75 as also more fully described in the earlier Letters Patent. After the tacking is completed, the form carrier 6 is swung forwardly by the lever 16, and the operator is then enabled, by downward movement of 80 the lever 134 and by rearward swinging movement of the member 118, to release the upper and then to remove from the form the upper and insole unit now permanently secured together at the heel end. 85

While the invention is herein described in its application to welt shoe work, it will be understood that in various novel and useful aspects it is not limited to that type of work. 90

Having described the invention, what I claim as new and desire to secure by Letters Patent of the United States is:—

1. In a machine of the class described, the combination with a form, of means for 100 tensioning forwardly about the form an upper the toe end portion of which has been previously molded substantially to the shape desired for the finished shoe, said upper-tensioning means being constructed and arranged to take its tensioning purchase on the forepart of the upper without impairing the molding of the toe. 105

2. In a machine of the class described, the combination with a form, of means for 110 tensioning forwardly about the form an upper the toe end portion of which has been previously molded substantially to the shape desired for the finished shoe, said upper-tensioning means being constructed and arranged to take its tensioning purchase on the molded toe portion of the upper without impairing the molding of that portion. 115

3. In a machine of the class described, the combination with a form, of means for 120 tensioning forwardly about the form an upper the toe end portion of which has been previously molded substantially to the shape desired for the finished shoe, said upper-tensioning means comprising a member constructed and arranged to take its tensioning purchase on the inner face of the end of the molded toe and having its upper-engaging face curved to conform substantially to the contour of the part that it engages. 125

4. In a machine of the class described, the combination with a form, of means for tensioning forwardly about the form an upper the toe end portion of which has been previously molded substantially to the shape desired for the finished shoe, said upper-tensioning means comprising an upper-pulling member shaped to extend upwardly and rearwardly and then downwardly and forwardly into position to take its tensioning purchase on the inner face of the end of the molded toe.

5. In a machine of the class described, the combination with a form, of means for tensioning forwardly about the form an upper the toe end portion of which has been previously molded substantially to the shape desired for the finished shoe with an in-turned marginal flange thereon, said upper-tensioning means comprising an upper-pulling member constructed and arranged to hook under said inturned flange and to take its tensioning purchase on the inner face of the end of the molded toe.

25 6. In a machine of the class described, the combination with a form, of means for tensioning forwardly about the form an upper the toe end portion of which has been previously molded substantially to the shape desired for the finished shoe with an in-turned marginal flange thereon, said upper-tensioning means comprising an upper-pulling member constructed and arranged to take its tensioning purchase on the inner face of the end of the molded toe under said inturned flange and to support the forepart of the upper at a predetermined height relatively to the bottom of the form by engaging said flange.

35 40 7. In a machine of the class described, the combination with a form, of means for tensioning forwardly about the form an upper the toe end portion of which has been previously molded substantially to the shape desired for the finished shoe with an in-turned marginal flange thereon, said upper-tensioning means comprising an upper-pulling member curved to extend about the end of the molded toe both heightwise and lengthwise of the toe with its end portion directed forwardly into position to engage the inner face of the end of the molded toe under said inturned flange.

55 8. In a machine of the class described, the combination with a form, of means for tensioning an upper forwardly about the form, said upper-tensioning means comprising an upper-pulling device constructed and arranged to take its tensioning purchase on the forepart of the upper and to move lengthwise of the upper to tension it, said device being also mounted for movement laterally of the form in response to resistance of the upper.

60 65 9. In a machine of the class described, the

combination with a form, of means for tensioning an upper forwardly about the form, said upper-tensioning means comprising an upper-pulling device constructed and arranged to take its tensioning purchase on the forepart of the upper and so mounted as to be free to move laterally of the form in response to resistance of the upper, and adjustable means for variably limiting the lateral movements of said device in opposite directions.

10. In a machine of the class described, the combination with a form, of means for tensioning forwardly about the form an upper the toe end portion of which has been previously molded substantially to the shape desired for the finished shoe, said upper-tensioning means comprising an upper-pulling member constructed and arranged to take its tensioning purchase on the inner face of the end of the molded toe and mounted for movements laterally of the form in response to resistance of the upper.

11. In a machine of the class described, the combination with a form, of means for tensioning an upper forwardly about the form, said upper-tensioning means comprising an upper-engaging device and spring means tending to move said device forwardly lengthwise of the form for pulling the upper while permitting the operator to move it rearwardly into position to take its tensioning purchase on the upper.

12. In a machine of the class described, the combination with a form, of means for tensioning an upper forwardly about the form, said upper-tensioning means comprising an upper-engaging device arranged to be moved by the operator rearwardly lengthwise of the form into position to take its tensioning purchase on the upper, and spring means arranged to act automatically on said device to tension the upper upon the release of the device by the operator.

13. In a machine of the class described, the combination with a form, of means for tensioning forwardly about the form an upper the toe end portion of which has been previously molded substantially to the shape desired for the finished shoe with an in-turned marginal flange thereon, said upper-tensioning means comprising a member formed to hook under said flange and to take its tensioning purchase on the inner face of the end of the molded toe, and spring means tending to move said member in the direction to pull the upper and against the resistance of which the operator is enabled to move said member into position to connect with the upper.

14. In a machine of the class described, the combination with a form, of means for tensioning an upper forwardly about the form, said upper-tensioning means comprising an upper-engaging device operatively

- movable lengthwise of the form, means for operating said device to subject the upper to comparatively light tension enabling the operator to adjust the upper about the form, and additional means for thereafter operating said device to subject the upper to increased tension.
15. In a machine of the class described, the combination with a form, of means for tensioning an upper forwardly about the form, said upper-tensioning means comprising an upper-engaging device operatively movable lengthwise of the form, spring means tending to move said device forwardly while permitting the operator to move it rearwardly into position to take its tensioning purchase on the upper, said spring means being arranged to subject the upper to comparatively light tension when the operator releases the upper-engaging device, and additional means for thereafter operating said device to subject the upper to increased tension.
16. In a machine of the class described, the combination with a form, of means for tensioning an upper forwardly about the form, said upper-tensioning means comprising a lever having an upper-engaging device thereon, and spring means arranged to act on said lever to swing the upper-engaging device forwardly to pull an upper and against the resistance of which the operator is enabled to swing said upper-engaging device rearwardly into position to take its tensioning purchase on the upper.
17. In a machine of the class described, the combination with a form, of means for tensioning an upper forwardly about the form, said upper-tensioning means comprising a lever extending heightwise of the form and having an upper-engaging device on its upper end, and spring means acting on the lower end portion of said lever to swing said upper-engaging device forwardly to tension the upper.
18. In a machine of the class described, the combination with a form, of means for tensioning an upper forwardly about the form, said upper-tensioning means comprising a lever mounted for operative swinging movement lengthwise of the form and having an upper-engaging device thereon, means for operating said lever to subject the upper to comparatively light tension enabling the operator to adjust the upper about the form, and additional means for thereafter operating said lever to subject the upper to increased tension.
19. In a machine of the class described, the combination with a form, of means for tensioning an upper forwardly about the form, said upper-tensioning means comprising a lever mounted for operative swinging movement lengthwise of the form and having an upper-engaging device thereon, a spring ar-
- ranged to act on said lever to subject the upper to comparatively light tension enabling the operator to adjust the upper about the form, and means arranged to act on said lever in a different location from the spring to subject the upper thereafter to increased tension.
20. In a machine of the class described, the combination with a form, of means for tensioning an upper forwardly about the form, said upper-tensioning means comprising a lever fulcrumed between its opposite ends and having at one side of its fulcrum means for engaging the upper and at the other side of its fulcrum spring means for operating it to pull the upper, and additional means arranged to act on the lever at the same side of its fulcrum as said upper-engaging means to subject the upper to increased tension.
21. In a machine of the class described, the combination with a form, of means for tensioning an upper forwardly about the form, said upper-tensioning means comprising a lever having an upper-engaging device thereon and provided with a cam face, and means movable along said cam face to swing said upper-engaging device forwardly to tension the upper.
22. In a machine of the class described, the combination with a form, of means for tensioning an upper forwardly about the form, said upper-tensioning means comprising a lever having an upper-engaging device thereon, and a hand lever extending transversely of said first lever adjacent to the latter and movable relatively to said first lever for operating it to tension the upper.
23. In a machine of the class described, the combination with a form, of means for tensioning an upper forwardly about the form, said upper-tensioning means comprising a lever having an upper-engaging device thereon, and a hand lever extending in a direction transverse to said first lever and provided with means for wedging the latter forwardly to tension the upper, said levers being constructed to interlock for maintaining the upper-engaging device in upper-tensioning position.
24. In a machine of the class described, the combination with a form, of means for tensioning an upper forwardly about the form, said upper-tensioning means comprising a lever having an upper-engaging device thereon, a spring arranged to act on said lever to subject the upper to comparatively light tension, and means for shifting the fulcrum point of said lever to a greater distance from the spring to increase the effective force of the spring in its action on the upper.
25. In a machine of the class described, the combination with a form, of means for tensioning an upper forwardly about the form, said upper-tensioning means compris-

ing a lever fulcrumed between its opposite ends and having at one side of its fulcrum means for engaging the upper and at the other side of its fulcrum spring means for 5 operating it to pull the upper, and means for shifting the fulcrum point of said lever toward the upper-engaging means to increase the effective force of the spring means in its action on the upper.

10 26. In a machine of the class described, the combination with a form, of means for tensioning an upper forwardly about the form, said upper-tensioning means comprising a lever having an upper-engaging device 15 thereon, spring means arranged to act on said lever to subject the upper initially to a comparatively light tension, and means for thereafter operating said lever to subject the upper to increased tension and for shifting 20 the fulcrum point of the lever to a greater distance from said spring means to increase the effective force of said means in its action on the upper.

25 27. In a machine of the class described, the combination with a form, of means for tensioning an upper forwardly about the form, said upper-tensioning means comprising a lever fulcrumed between its opposite ends and having at one side of its fulcrum 30 means for engaging the upper and at the other side of its fulcrum spring means for operating it to pull the upper, and means constructed and arranged to act on said lever at the same side of the fulcrum as its 35 upper-engaging means to increase the tension of the upper and to provide a second fulcrum for the lever nearer to the upper-engaging means than its first fulcrum.

40 28. In a machine of the class described, the combination with a form, of means for tensioning an upper forwardly about the form, said upper-tensioning means comprising a lever having an upper-engaging device 45 thereon, spring means arranged to act on said lever to subject the upper to comparatively light tension, and additional means arranged to act on the lever to increase the tension of the upper and to move the lever bodily forward in the direction of the pull 50 on the upper.

55 29. In a machine of the class described, the combination with a form, of means for tensioning an upper forwardly about the form, said upper-tensioning means comprising a lever having an upper-engaging device 60 thereon, spring means for swinging said lever to tension the upper, and additional means for swinging the lever in the same direction as said spring means and for thereafter swinging it substantially about the point of engagement of said device with the upper against the resistance of said spring means to increase the tension of the upper.

65 30. In a machine of the class described, the combination with a form, of means for

tensioning an upper forwardly about the form, said upper-tensioning means comprising a lever having a fulcrum pin between its opposite ends and provided at one end with upper-engaging means and at the other end with spring means for swinging it to tension the upper, an abutment for said fulcrum pin provided with a slot to permit said pin to move forwardly substantially in the direction of the pull on the upper, and means for engaging the lever at the same side of its fulcrum as its upper-engaging means for swinging it in the same direction as said spring means and for thereafter operating it to move its fulcrum pin forwardly in its slot to increase the tension of the upper. 70 75 80

31. In a machine for molding the heel end of an upper off the last, the combination with molding means, and a heel-end form movable from an upper-receiving position to present an upper having a previously molded toe to said molding means, of means movable with the form for engaging the molded toe and holding the upper under 90 forward tension about the form. 85

32. In a machine for molding off the last the heel end of an upper the toe end of which has been previously molded substantially to the shape desired for the finished shoe, the 95 combination with molding means and a heel-end form movable from an upper-receiving position to present an upper to said molding means, of means movable with the form for tensioning the upper forwardly about the 100 form, said upper-tensioning means being constructed to take its tensioning purchase on the forepart of the upper without impairing the molding of the toe.

33. In a machine of the class described, 105 the combination with a heel-end form, of means for tensioning an upper forwardly about the form, and means for positioning an insole in predetermined relation to the form including a device for supporting the 110 toe end of the insole independently of the form.

34. In a machine of the class described, the combination with a form and means for shaping over the form the heel end of an 115 upper the toe end portion of which has been previously molded substantially to the shape desired for the finished shoe, of upper-positioning means for engaging the heel end of the upper in one or more jig holes provided 120 therein to position the upper relatively to the form, and means for engaging the molded toe end of the upper to subject the upper to forward tension sufficient to hold it about the form while permitting the operator to adjust it relatively to the form and to said upper-positioning means. 125

35. In a machine of the class described, the combination with a form and means for shaping over the form the heel end of an 130

upper the toe end portion of which has been previously molded substantially to the shape desired for the finished shoe, of upper-positioning means for engaging the heel end of 5 the upper in one or more jig holes provided therein to position the upper relatively to the form, and means for engaging the molded toe end of the upper to tension the upper lightly about the form while permitting the 10 operator to adjust it relatively to the form and to said upper-positioning means and for thereafter increasing the tension of the upper to tighten it about the form.

36. In a machine of the class described, the 15 combination with a form and means for shaping over the form the heel end of an upper the toe end portion of which has been previously molded substantially to the shape desired for the finished shoe, of means for 20 engaging the heel end of the upper in one or more jig holes provided therein to position the upper relatively to the form, and means for engaging the molded toe end of the upper to position it in predetermined relation 25 to the form and to tension the upper forwardly about the form.

37. In a machine of the class described, the combination with a form and means for shaping over the form the heel end of an 30 upper the toe end portion of which has been previously molded substantially to the shape desired for the finished shoe, of means for 35 engaging the heel end of the upper in one or more jig holes provided therein to position the upper relatively to the form, and means for engaging the molded toe end of the upper to support the forepart of the upper at a predetermined height relatively to the form and to tension the upper forwardly 40 about the form.

38. In a machine of the class described, the combination with a form, and means for shaping over the form the heel end of an upper the toe end portion of which has been 45 previously molded substantially to the shape desired for the finished shoe with an in-turned marginal flange thereon, of means for engaging the heel end of the upper in one or more jig holes provided therein to position the upper relatively to the form, and means for engaging the molded toe end of the upper under said inturned flange to support the forepart of the upper by said 50 flange at a predetermined height relatively 55 to the form.

39. In a machine of the class described, the combination with means for shaping the heel end of an upper over a form, and a form movable from an upper-receiving position to 60 present the upper to said upper-shaping means, of means movable with the form for engaging the heel end of the upper in one or more jig holes provided therein to position the upper relatively to the form, and a de-

vice also movable with the form for tensioning the upper forwardly about the form. 65

40. In a machine of the class described, the combination with a form over which to mold the heel end of an upper off the last, and means for molding the upper over said 70 form and over an insole on the form, of a device for engaging the forepart of the upper and tensioning the upper forwardly about the form, said upper-tensioning device being constructed and arranged to support 75 the forepart of the insole.

41. In a machine of the class described, the combination with a form over which to mold the heel end only of an upper off the last, and means for molding said upper over 80 the form and over an insole on the form, of a device for tensioning the upper forwardly about the form, and means for positioning the insole in predetermined relation to the form including a device for supporting the toe end of the insole. 85

42. In a machine of the class described, the combination with means for shaping the heel end of an upper over a form and for laying the margin of the upper inwardly 90 over an insole on the form, and a form movable from a work-receiving position into position to present the upper and the insole to said upper-shaping means, of devices arranged to be rendered operative while the 95 form is in work-receiving position to tension the upper forwardly about the form and to clamp the insole on the form, said devices being movable with the form and arranged 100 to remain in upper-tensioning and insole-clamping position during a portion at least of the operation of laying the margin of the upper inwardly over the insole.

43. In a machine of the class described, the combination with means for shaping the 105 heel end of an upper over a form and for laying its margin inwardly over an insole on the form, and a form movable from a work-receiving position into position to present the upper and the insole to said upper-shaping means, of a device arranged to 110 clamp the heel end of the insole on the form during such movement of the form and to remain in clamping position during a portion at least of the operation of laying the 115 margin of the upper inwardly over the insole.

44. In a machine of the class described, the combination with means for shaping the heel end of an upper over a form and for wiping its margin inwardly over an insole provided with a welt-attaching lip and against the rear end portions of said lip, and a form movable from a work-receiving position into position to present the upper 120 and the insole to said upper-shaping means, of a device for clamping the heel end of 125 the insole on the form and for supporting

the rear end portions of the lip against the pressure of the wiping means, said device being arranged to move with the form and to remain in operative position until after 5 the margin of the upper has been wiped inwardly.

45. In a machine of the class described, the combination with a form and means for shaping the heel end of an upper over the 10 form and for laying the upper inwardly over the margin of an insole on the form, of a device for clamping the heel end of the insole on the form at a distance from the edge of the insole, and a device for 15 applying clamping pressure over the margin of the heel end of the insole, said clamping devices being relatively movable to permit the margin-clamping device to be withdrawn from operative position while the other 20 clamping device remains in operative position.

46. In a machine of the class described, the combination with a form and means for shaping the heel end of an upper over the 25 form and for laying the upper inwardly over the margin of an insole provided with a welt-attaching lip and against the rear end portions of said lip, of a device formed and arranged to clamp the heel end of the 30 insole on the form at a distance from the edge of the insole and to support the rear end portions of the lip against the overlaying pressure, and a device for applying clamping pressure over the margin of the 35 heel end of the insole rearwardly of the ends of said lip, said clamping devices being relatively movable to permit the margin-clamping device to be withdrawn from operative 40 position while the other device remains in operative position.

47. In a machine of the class described, the combination with a form and means for shaping the heel end of an upper over the 45 form and for laying the upper inwardly over the margin of an insole on the form, of a device for clamping the heel end of the insole on the form at a distance from the edge of the insole, a separate clamping device arranged to occupy an operative position over the margin of the heel end of the insole while the other device is in operative position, and means for withdrawing said 50 margin-clamping device from operative position prior to the laying of the upper inwardly over the insole while maintaining the other clamping device in operative position during a portion at least of the overlaying operation.

48. In a machine of the class described, the combination with a form and means for shaping the heel end of an upper over the 60 form and for laying the upper inwardly over the margin of an insole on the form, of a device for clamping the heel end of the insole on the form at a distance from

the edge of the insole, a separate clamping device arranged to occupy an operative position over the margin of the heel end of the insole while the other device is in operative position, and automatic means for 70 withdrawing said clamping devices successively from operative position in time relation to the shaping of the upper.

49. In a machine of the class described, the combination with a form and means for 75 shaping the heel end of an upper over the form and for laying the upper inwardly over the margin of an insole on the form, of a support movable heightwise of the form, a clamping device carried by said 80 support for applying clamping pressure to the insole at a distance from the edge of the insole, another clamping device carried by said support for applying clamping pressure over the margin of the insole, and 85 spring means for controlling said first-named clamping device to cause it to remain in operative position while the margin-clamping device is withdrawn from operative position by movement of said support.

50. In a machine of the class described, the combination with a form and means for shaping over the form and over an insole on the form the heel end portion of upper 95 materials including a flanged counter, of a device for clamping the heel end of the insole on the form at a distance from the edge of the insole, and a device for pressing the flange of the counter down over the margin of the insole while said clamping device is in operative position, said devices being relatively movable to permit the counter-pressing device to be withdrawn from 100 operative position while the other device remains in operative position.

51. In a machine of the class described, the combination with a form and means for shaping over the form and over a welt shoe insole on the form the heel end portion of 110 upper materials including a flanged counter and for laying the margin of the upper inwardly over the insole and against the rear end portions of the insole lip, of a device for engaging the rear end portions of the 115 insole lip to support the lip against the overlaying pressure on the upper, a device for positioning the counter in predetermined relation to the form while the lip-supporting device is in operative position, and a 120 common support for said different devices upon which they are relatively movable to permit the counter-positioning device to be withdrawn from operative position while the lip-supporting device remains in operative position.

52. In a machine of the class described, the combination with means for shaping the heel end of an upper over a form and for laying the upper inwardly over the mar- 130

- gin of an insole on the form, and a form movable from a work-receiving position into position to present the upper and the insole to the upper-shaping means, of separate devices for applying clamping pressure respectively at a distance from the edge of the insole and over the margin of the insole, said 5 clamping devices being movable with the form while in clamping position, and means 10 for withdrawing the margin-clamping device thereafter from clamping position while the other device remains in clamping position.
53. In a machine of the class described, 15 the combination with a form and means for shaping over the form and over a welt shoe insole on the form the heel end portion of upper materials including a flanged counter and for laying the margin of the upper inwardly over the insole and against the rear end portions of the insole lip, and a form 20 movable from a work-receiving position into position to present the upper and the insole to the upper-shaping means, of a device for 25 engaging the rear end portions of the insole lip to support the lip against the overlaying pressure on the upper, and a device for positioning the counter in predetermined relation to the form, both said 30 devices being movable with the form from work-receiving to work-presenting position and relatively movable thereafter to permit the counter-positioning device to be withdrawn from operative position while the 35 lip-supporting device remains in operative position.
54. In a machine of the class described, 40 the combination with a form and means for shaping the heel end of an upper over the form and for laying the upper inwardly over the margin of an insole on the form, of a support movable heightwise of the form, separate devices carried by said support for applying clamping pressure respectively at 45 a distance from the edge of the insole and over its margin, means for controlling said clamping devices to cause the margin-clamping device to be withdrawn from clamping position by upward movement of the support and to cause the other clamping device to be withdrawn by further upward movement of the support, spring means for 50 moving said support upwardly, a device for retaining the support against upward movement, and automatic means for controlling said retaining device to cause the support to receive different upward movements in succession to withdraw the clamping devices successively from operative position.
55. In a machine of the class described, 55 the combination with a form and means for shaping the heel end of an upper over the form and over an insole on the form, of devices for positioning the upper and the insole respectively in relation to the form,
- said devices being movable as a unit toward and from operative position and relatively movable heightwise of the form to permit the upper-positioning device to be withdrawn from operative position while the 70 insole-positioning device remains in operative position.
56. In a machine of the class described, 75 the combination with a form and means for shaping the heel end of an upper over the form and for laying its margin inwardly over an insole provided with a welt-attaching lip and against the rear end portions of 80 said lip, of a device for supporting the rear end portions of said lip against the overlaying pressure on the upper, and an upper-positioning device having means for engaging the upper in one or more jig holes formed therein, said devices being movable as a unit toward and from operative position and relatively movable to permit the upper-positioning device to be withdrawn from operative position while the lip-supporting device remains in operative position.
57. In a machine of the class described, 90 the combination with means for shaping the heel end of an upper over a form and for laying its margin inwardly over an insole provided with a welt-attaching lip and against the rear end portions of said lip, 95 and a form movable from an upper-receiving position into position to present the upper and the insole to the upper-shaping means, of a device for supporting the rear end portions of the insole lip against the overlaying pressure on the upper, an upper-positioning device having means for engaging the upper in one or more jig holes formed therein, said devices being movable with the form in operative relation to the 100 insole and the upper, and means for withdrawing the upper-positioning device from operative position while the lip-supporting device remains in operative position.
58. In a machine of the class described, 110 the combination with a form and means for shaping the heel end of an upper over the form and over an insole on the form, of a device for clamping the insole on the form, an upper-positioning device having means 115 for engaging the upper in one or more jig holes formed therein, and a common support for said devices to carry them toward and from operative position, said devices being relatively movable on their support to 120 permit the upper-positioning device to be withdrawn from operative position heightwise of the form while the insole-clamping device remains in operative position.
59. In a machine of the class described, 125 the combination with a form and means for shaping the heel end of an upper over the form and over an insole on the form, of a device for clamping the insole on the form, an upper-positioning device comprising a 130

- member having jig pins movably mounted thereon for engaging the upper in jig holes formed therein, a common support for said devices movable heightwise of the form, and 5 controlling means automatically operative upon movement of the support away from the form to withdraw the jig pins from the upper, then to retract them from the form while the insole-clamping device remains in 10 clamping position, and thereafter to withdraw said clamping device from the insole.
60. In a machine of the class described, the combination with means for shaping the heel end of an upper over a form and for laying its margin inwardly over an insole on the 15 form, and a form movable from a work-receiving position into position to present the upper and the insole to said upper-shaping means, of a device for clamping the insole 20 on the form, and an upper-positioning device having means for engaging the upper in one or more jig holes formed therein, said devices being movable with the form from work-receiving to work-presenting position 25 and relatively movable thereafter to permit the upper-positioning device to be withdrawn from the form while the clamping device remains in operative position.
61. In a machine of the class described, 30 the combination with a form and means for shaping the heel end of an upper over the form and for laying the upper inwardly over the margin of an insole on the form, of a device for clamping the heel end of the insole on the form at a distance from the edge 35 of the insole, a device for applying clamping pressure over the margin of the heel end of the insole, said clamping devices being relatively movable to permit the margin-clamping 40 device to be withdrawn from operative position while the other clamping device remains in operative position, and upper-positioning means for engaging the upper in one or more jig holes formed therein, said upper- 45 positioning means being movable with the margin clamping device out of operative position.
62. In a machine of the class described, 50 the combination with a form and means for shaping the heel end of an upper over the form and for laying the upper inwardly over the margin of an insole on the form, of separate devices relatively movable heightwise of the form and arranged respectively 55 to apply clamping pressure at a distance from the edge of the insole and over its margin, said margin-clamping device having thereon means for engaging the upper in one or more jig holes formed therein to position 60 the upper, and means for withdrawing said margin-clamping device and its upper-positioning means from operative position while the other clamping device remains in operative position.
65. In a machine of the class described, 65 the combination with a form and means for shaping the heel end of an upper over the form and for laying the upper inwardly over the margin of an insole on the form, of a support movable heightwise of the form, 70 separate devices carried by said support for applying clamping pressure respectively at a distance from the edge of the insole and over its margin, upper-positioning means carried by said margin-clamping device comprising one or more jig pins movable relatively to said device into or out of position to engage the upper in one or more jig holes formed therein, and means automatically operative upon movement of said support 75 heightwise of the form to disconnect said upper-positioning means from the upper, then to move said upper-positioning means and the margin-clamping device away from the form, and thereafter to withdraw the 80 other clamping device from the form.
64. In a machine of the class described, the combination with a form and means for shaping the heel end of an upper over the form and for laying the upper inwardly over the margin of an insole on the form, of 85 separate devices arranged respectively to apply clamping pressure at a distance from the edge of the insole and over its margin simultaneously, said devices being relatively movable heightwise of the form, upper-positioning means carried by said margin-clamping device comprising one or more jig pins for 90 engaging the upper in one or more jig holes formed therein, and automatic means for disconnecting said upper-positioning means from the upper and for withdrawing said means and the margin-clamping device from the form prior to the laying of the upper inwardly over the insole and for withdrawing the other clamping device from operative 95 position after the overlaying operation has been substantially completed.
65. In a machine of the class described, 100 the combination with a form and means for shaping over the form and over an insole on the form the heel end portion of upper materials including a flanged counter, of an insole-clamping member and a counter-positioning member relatively movable to permit the latter to be withdrawn from operative position while the clamping member remains in operative position, and upper-positioning means movable out of operative position with said counter- 105 positioning member.
66. In a machine of the class described, 110 the combination with a form and means for shaping over the form and over a welt shoe insole on the form the heel end portion of upper materials including a flanged counter and for laying the upper over the margin of the insole and against the rear end portions of the insole lip, of a device for supporting 115 the rear end portions of said lip against the 120
65. In a machine of the class described, 125 the combination with a form and means for shaping over the form and over a welt shoe insole on the form the heel end portion of upper materials including a flanged counter and for laying the upper over the margin of the insole and against the rear end portions of the insole lip, of a device for supporting 130 the rear end portions of said lip against the

- pressure of the overlaying means, a member for pressing the flange of the counter toward the insole, said member being movable relatively to the lip-supporting device to withdraw it from operative position while said device remains in operative position, and upper-positioning means movable out of operative position with said flange-pressing member.
- 10 67. In a machine of the class described, the combination with means for shaping over a form and over a welt shoe insole on the form the heel end portion of upper materials including a flanged counter and for laying the upper inwardly over the insole and against the rear end portions of the insole lip, and a form movable from a work-receiving position into position to present the upper and the insole to said upper-shaping means, of devices movable with the form for supporting the rear end portions of the insole lip against the overlaying pressure on the upper, for pressing the flange of the counter toward the insole, and for engaging the upper in one or more jig holes formed therein to position the upper relatively to the form.
- 15 68. In a machine of the class described, the combination with means for shaping an upper over a form, and a form movable from a work-receiving position into position to present the work to said upper-shaping means, of work-positioning means co-operating with the form and movable therewith from work-receiving to work-presenting position, and means also movable with the form for imparting to said work-positioning means movement heightwise of the form to withdraw it from operative position.
- 20 69. In a machine of the class described, the combination with means for shaping an upper over a form, and a form movable from a work-receiving position into position to present the work to said upper-shaping means, of work-positioning means co-operating with the form and movable therewith from work-receiving to work-presenting position, said work-positioning means being movable heightwise of the form to operative position when the form is in work-receiving position, and spring means movable with the form for imparting to said work-positioning means reverse movement heightwise of the form when the form is in work-presenting position.
- 25 70. In a machine of the class described, the combination with means for shaping an upper over a form, and a form mounted for swinging movement rearwardly from a work-receiving position into position to present the work to said upper-shaping means, of a work-positioning device mounted independently of the form to swing about the same axis as the form, said device being movable into operative relation to the form when the form is in work-receiving position, and means for withdrawing said device from the form and for swinging it forwardly about the axis of the form when the form is in work-presenting position.
- 30 71. In a machine of the class described, the combination with means for shaping an upper over a form, and a form mounted for swinging movement rearwardly from a work-receiving position into position to present the work to said upper-shaping means, of a work-positioning device mounted independently of the form to swing about the same axis as the form, said device being also movable heightwise of the form into and out of operative position, means for moving said device heightwise of the form and for connecting it to the form when the form is in work-receiving position, and means for disconnecting said device from the form and for swinging it forwardly while the form is in work-presenting position.
- 35 72. In a machine of the class described, the combination with means for shaping an upper over a form, and a form mounted for swinging movement rearwardly from a work-receiving position into position to present the work to said upper-shaping means, of a work-positioning device arranged to be positioned over the bottom of the form, an arm supporting said device and mounted for swinging movement laterally of the form, a support for said arm mounted for movement heightwise of the form, and a guide for said support mounted to swing about the same axis as the form.
- 40 73. In a machine of the class described, the combination with means for shaping an upper over a form, and a form mounted for swinging movement rearwardly from a work-receiving position into position to present the work to said upper-shaping means, of a work-positioning device arranged to be positioned over the bottom of the form, an arm supporting said device and mounted for swinging movement laterally of the form, a support for said arm mounted for movement heightwise of the form, a guide for said support mounted for swinging movement about the same axis as the form, means for moving said support downwardly along its guide to carry the work-positioning device toward the bottom of the form after said arm has been swung to position the device over the form, and spring means for subsequently imparting reverse upward movement to said support and reverse swinging movement to said arm.
- 45 74. In a machine of the class described, the combination with means for shaping an upper over a form, and a form mounted for swinging movement rearwardly from a work-receiving position into position to present the work to said upper-shaping means, of a work-positioning device arranged to be positioned over the bottom of the form,

an arm supporting said device and mounted for swinging movement laterally of the form, a support for said arm mounted for movement heightwise of the form, a guide 5 for said support mounted for swinging movement about the same axis as the form, means for moving said support downwardly along its guide to carry the work-positioning device toward the bottom of the form when 10 the form is in work-receiving position, and means for imparting reverse upward movement to said support and for swinging said support and its guide forwardly about the axis of the form when the form is in work- 15 presenting position.

75. In a machine of the class described, the combination with a form, and means for

shaping an upper over the form, of upper-positioning means comprising a jig pin for engaging the upper in a jig hole formed 20 therein, said jig pin being curved to serve as a hook for supporting the upper.

76. In a machine of the class described, the combination with a form, and means for shaping an upper over the form, of upper-positioning means comprising a jig pin for engaging the upper in a jig hole formed 25 therein, said jig pin being mounted for swinging movement into and out of operative position and curved about the axis of 30 its swinging movement.

In testimony whereof I have signed my name to this specification.

WILLIAM C. BAXTER.
